UNITED STATES PATENT OFFICE.

JOHN GEORGE HESS, OF ADAMSTON, WEST VIRGINIA.

GAS-BURNER FOR FURNACES.

1,311,515.

Specification of Letters Patent. Patented July 29, 1919.

Application filed March 22, 1919. Serial No. 284,289.

To all whom it may concern:

Be it known that I, JOHN GEORGE HESS, a citizen of the United States, residing at Adamston, in the county of Harrison and 5 State of West Virginia, have invented a new and useful Gas-Burner for Furnaces, of which the following is a specification.

This invention relates to improvements in gas burners for furnaces, the object of the 10 invention being to provide an improved burner for furnaces which are known as continuous heating furnaces, by means of which a thorough intermingling of the gas and heated air before entrance into the combustion chamber is accomplished.

A further object of the invention is to provide a burner which may be used for either natural or artificial gas without the necessity of rebuilding the furnace.

20 A further object of the invention is the provision of a burner of the character set forth which is comparatively simple in construction and extremely economical in operation.

25 With these and other objects in view, which will appear as the description proceeds, the invention consists in the novel features of construction and combination of parts which will be more fully set forth 30 hereinafter and particularly pointed out in the claims.

In the burners heretofore in use with which I am familiar, the gas is conducted through one flue and the air through another, usually on top of the gas flue; consequently the gas comes in contact with the air on one side only, which results in a waste of fuel. Moreover, when it is desired to force the furnace to create a higher degree of heat 40 it frequently happens that the gas will smoke because of insufficient mixing with hot air. Furthermore, furnaces intended for the use of natural gas were built with only one set of checkers, since natural gas is led into the furnace directly from the side without preheating, while artificial or producer gas requires preheating, and for this reason should it become necessary to resort to the use of artificial gas, as is frequently the case, this can only be done by building an additional set of checkers, and as in many furnaces there is not sufficient room for this additional set of checkers it is necessary to go to the enormous expense

of tearing out the entire furnace and re-building the same.

The present invention aims to overcome the defects referred to and to produce a burner in which the air is supplied to the gas in such a manner that a perfect intermingling is obtained, which results in the consumption of all of the gas and producing better combustion and a brighter fire; and in addition, owing to the construction hereinafter set forth, should it become necessary 60 to change from the use of natural gas to artificial or producer gas the necessity for building an additional set of checkers is avoided, since, owing to the relative locations of the gas and air flues, the gas is preheated by the 65 air which has been heated in the checker chamber to a very much higher degree than in the furnaces as ordinarily constructed.

In the drawings accompanying and forming part of this specification, and in which 70 only so much of a furnace is shown as is necessary to illustrate my invention,

Figure 1 is a sectional plan view of the combustion chamber of a continuous heating furnace embodying my improved burner;

Fig. 2 is a vertical section on an enlarged scale, taken on the line 2—2 of Fig. 1, looking in the direction of the arrows, and showing the arrangement of gas and air ducts; and

Fig. 3 is a horizontal section through my improved burner adapted for the use of natural gas.

The same characters of reference designate the same parts in the different figures 90 of the drawings.

In the embodiment herein illustrated, 2 designates the combustion chamber reinforced by the usual I-beams 3 and having the usual conduits 4 leading to the stack 5 and provided with a reversing valve 6. Since the operation of such reversing valves is well known and forms no part of my invention, I have not considered it necessary 95 to illustrate herein the mechanism by which the same is reversed. Neither is it deemed necessary to illustrate the manner in which the air is led through the checker chambers for preheating such air, since this also is well known in the art.

Fig. 1 shows four of my improved burners arranged on either side of the combustion chamber 2, a gas supply tube or conduit 7

extending over each series of burners and communicating therewith, each conduit being provided with a water sealed valve 8 for controlling the supply of gas to the burner. As shown in Fig. 2, the burner is constructed on top of the checker chamber 9 through which the air is passed for pre-heating the same, and in the present instance the burner consists of a pair of air ducts or flues 10 communicating at their lower ends with the checker chamber, and a gas flue 11 located between said air flues and extending some distance downwardly between said air flues. Each of the gas flues 11 is entirely closed at its lower end, as clearly shown in Fig. 2, and communicates at its upper end with the conduit or supply pipe 7; whereby is formed a pocket between the two air flues within which the gas delivered from the pipe 7 is trapped and thus receives a preliminary heating by reason of its contact with the heated walls of the air flues. In the practical use of the burner it is contemplated that a depth of twelve feet will be sufficient for the purpose desired. The gas and air flues merge just prior to entering the combustion chamber into a single port 12, as shown in Fig. 1, where combustion takes place.

In the use of the structure above set forth, when the reversing valve is set as shown in Fig. 1, cold air is drawn in through the port 13 in the conduit 4 and is conducted through the checker chambers at the right-hand side of Fig. 1, and thence upwardly through the air flues 10, mingling with the gas at 12, where combustion takes place. The products of combustion are then drawn across the combustion chamber and down through the air flues at the opposite or left-hand side of the combustion chamber and through the checker chambers below the same, whereby the checker chambers are heated to a high temperature, the products of combustion then passing out through the conduit 4 at the left-hand side of Fig. 1 and up through the stack 5. When the checkers on that side are heated sufficiently, the valve 6 is reversed and cold air is now taken in through the conduit 4 at the left, passing through the checker chambers and in contact with the now highly heated checkers therein and then up through the air flues 10, by means of which the gas in the flue 11 between the flues 10 is also heated to the desired degree, combustion taking place at 12 as before described, the products of combustion being drawn across the combustion chamber toward the right and down the air flues, through the checker chambers and out through the conduit 4 to the stack. By thus alternating the circulation through the checker chambers and the combustion chamber the checkers on either side of the furnace are alternately heated to the desired

temperature to properly preheat the air before mingling with the gas, and the gas is also thoroughly heated by reason of the location of the gas duct or chamber 11 between the two air ducts 10.

In Fig. 3 I have shown the burner arranged for the use of natural gas. In this case the gas is delivered through small pipes 14 entering directly from the sides of the burner. It will thus be seen that in changing from the use of natural gas to artificial gas the only change necessary is to place the gas supply pipe above the burner so that the gas is delivered into the duct 11 to be heated by reason of the contiguity of said duct to the hot air ducts 10 on either side thereof. I do not desire to limit myself to any particular relative sizes between the ducts 10 and 11, but practical use has demonstrated that the most satisfactory results are obtained by making the gas duct approximately one-third larger than either of the air flues.

It will be observed from the foregoing that while I have made provision for the heating of the gas before mingling with the air, there is no checker chamber through which the gas must pass in order to be so heated. In furnaces as heretofore constructed, in which the gas was heated by passing the same through a checker chamber, every time the circulation was reversed more or less gas was left in the checker chamber to be carried off up the stack, and as such reversing ordinarily takes place at least three times an hour the loss from this reversing was considerable; but, by forming the gas ducts as herein described a pocket is formed wherein is retained any gas that may be in such ducts or pockets when the reversal takes place.

While I have described in detail the structure herein illustrated, it is to be understood that I do not thereby limit my invention to the precise features of construction shown, as I am aware that many mechanical changes may be made without departing from the spirit and scope of the invention as set forth in the appended claims.

Having thus described my invention, what I claim is:

1. In a gas furnace having a combustion chamber and a plurality of checker chambers, a burner associated with each of said checker chambers and comprising a pair of vertical air flues communicating at their lower ends with the checker chamber and a vertical gas flue located between said air flues; said gas flue being closed at its lower end and communicating at its upper end with a source of supply, whereby a pocket is formed adapted to trap the gas delivered from said supply and preheated by contact with the walls of the air flues, the gas and air flues associated with each checker chamber.

ber merging into a single port at the entrance to the combustion chamber.

2. In a gas furnace having a combustion chamber, a burner comprising a plurality of air ducts and a gas duct, said gas duct located centrally of said air ducts and extending in parallelism therewith, all of said ducts merging into a single port at the entrance to the combustion chamber, and said gas duct forming a gas-retaining pocket at the lower end thereof.

3. In a gas furnace having a combustion chamber and an air preheating chamber, a burner comprising a pair of air ducts communicating with said chambers, and a gas duct extending between said air ducts in parallelism therewith and in communication only with said combustion chamber, all of said ducts merging into a single port at the entrance to said combustion chamber and said gas duct forming a gas retaining pocket at its lower end.

4. In a gas furnace having a combustion chamber and a series of air preheating chambers, a series of burners, one for each preheating chamber and comprising a pair of air ducts in communication with said combustion chamber and said preheating chamber, a gas duct located between said air ducts and extending in parallelism therewith and in communication only with said combustion chamber, the ducts of each burner merging into a single port at the entrance to said combustion chamber, said gas ducts forming pockets at their lower ends, and means for reversing the direction of draft through said air ducts.

In testimony that I claim the foregoing as my own, I have hereto affixed my signature in the presence of two witnesses.

JOHN GEORGE HESS.
